UNITED STATES PATENT OFFICE.

JAMES M. HOPKINS, OF CHICAGO, ILLINOIS, ASSIGNOR TO CAMEL COMPANY, A CORPORATION OF MAINE.

BOTTOM DOOR-GUIDE FOR FREIGHT-CARS.

1,146,073.

Specification of Letters Patent.

Patented July 13, 1915.

Application filed February 23, 1915. Serial No. 10,028.

To all whom it may concern:

Be it known that I, JAMES M. HOPKINS, a citizen of the United States, residing at Chicago, in the county of Cook and State of Illinois, have invented certain new and useful Improvements in Bottom Door-Guides for Freight-Cars, of which the following is a specification.

My invention relates in general to freight cars, and more particularly to an improved bottom door guide for freight car doors.

Considerable force is required, and often much trouble experienced, in opening and closing the sliding side doors of freight cars. This fact is due to the weight of the doors; to the warping or distorting of the doors which impedes their free sliding on their guides; and to the necessity of the doors tightly engaging the frames around the door openings in order to render the cars weather and dust proof.

The primary object of my invention is to reduce the power required to open and close the sliding side doors of freight cars, and to avoid much of the trouble often incident thereto, by providing an improved bottom door guide which will reduce the frictional resistance to the movement of the doors and will at the same time efficiently guide the doors in their movement from open to tightly closed positions, and vice versa.

A further object of my invention is to provide an improved bottom door guide for freight cars which will not only support the doors against lateral movement away from the car sides but will, when the door sags, vertically support it with a minimum of resistance to its opening and closing movements.

A still further object of my invention is to provide an improved bottom guide for freight car doors which will be simple in construction, durable in use, efficient in operation, and convenient in application to the cars.

My invention will be more fully described hereinafter with reference to the accompanying drawings in which the same is illustrated as embodied in a convenient and practical form and in which:

Figure 1 is an enlarged vertical central section through the center of Fig. 2; Fig. 2 is an elevational view looking from the right in Fig. 1; Fig. 3 is a sectional view on line 4—4 of Figs. 1 and 2; and Fig. 4 is a somewhat

diagrammatic plan view showing the relation of the flange on the bottom of the car door to the series of guides secured to the car.

Similar reference characters are used to designate similar parts in the several figures of the drawings.

Reference character B designates a sliding door for controlling a door opening in the side of a freight car.

C designates the side sill of the car, and D a portion of the car floor at the bottom of the door opening.

The construction of the freight car does not in itself form part of my invention, and hence need not be more fully described and illustrated in order that my invention may be completely disclosed.

It will be understood that my invention is not limited in its use to a car of any particular construction, but may be used for guiding the bottom of the sliding door of a freight car of any construction.

My improved guide comprises a vertical base plate H adapted to be secured to the car side below the plane of the door opening, by any suitable fastening means, such for instance as bolts i passing through lugs h at opposite sides of the base plate H. Projecting outwardly from the top of the base plate H is a horizontal portion K having projecting from the outer edge thereof a vertical trunnion L. Supported upon the trunnion L is a roller l having a depression in its upper end within which is enclosed a washer L' fixed to the reduced upper end of the trunnion for retaining the roller in position upon the trunnion. The roller L engages the outer surface of the flange G depending below the bottom of the door, such flange being preferably a part of a Z-bar F secured to the bottom of the door B by any suitable means, such for instance as bolts f.

Extending above the horizontal portion K of the guide are inwardly converging curved flanges K' and K² located on opposite sides of the roller L, such flanges serving to guide the flange G into engagement with the roller L.

My improved guide may also be provided with a horizontal roller M projecting upwardly through an opening in the horizontal member K immediately below the flange G. The roller M is rotatably supported

upon an axle N, the inner end of which is supported by a circular bearing O projecting from the base plate H. The inner end of the axle N is provided with a head 5 n seated in a recess formed in the inner surface of the base plate H. The outer end of the axle N is supported in a circular bearing P. n' indicates a head formed on the outer end of the axle N to overlie the outer surface of the bearing P.

The base plate H, horizontal portion K, trunnion L, and bearings O and P, are all preferably formed in a single casting which may have the requisite strength imparted to it by means of reinforcing webs k', k'', k''' and k⁴.

Any desired number of my improved guides may be secured to the side of the car to engage the flange G on the door and insures the proper guiding of the bottom of the door during its movements into open and closed position. In Fig. 1 I have shown one of my improved brackets H' located adjacent the front of the door opening and another H³ located adjacent the rear of the door opening. Another guide H² is located below the center of the door opening, while a third H⁴ is located at one side of the door opening to guide and support the bottom of the door when it is in open position. The flange G depending below the bottom of the door B is preferably provided with outwardly projecting portions g¹ and g² located in position to engage the rollers of the guides H¹ and H³ when the door is in closed position, thereby insuring the door, when closed, being forced tightly against the frame around the door opening. In order that the outward projection g¹ on the flange G adjacent the front edge of the door may not impede the free opening and closing of the door through engagement with the roller on the guide H², such roller is preferably spaced outwardly from the car side a sufficient distance to permit the projection g¹ to freely pass the same. The roller on the guide H⁴ is also preferably spaced away from the car side a sufficient distance to be freely passed by the outward projection g² on the flange G adjacent the rear edge of the door. This arrangement of the guides with relation to the flange G is clearly shown in Fig. 4.

The engagement of the outer surface of the flange G with the rollers of the guides during the opening and closing movements of the door serves to reduce resistance to the movement of the door, and thereby render it unnecessary to exert the same power in order to open and close the door as is necessary when the bottom of the door engages fixed surfaces on the guides. The horizontal rollers on the guides are normally located slightly below the lower edge of the flange G, but when through the sag-

ging of the door, which frequently occurs in the usage of freight cars, the bottom of the flange engages the door guides, the movement of the door will be facilitated by the horizontal rollers which then vertically support the bottom of the door. While such horizontal rollers are preferably provided, yet my invention may also be practically embodied without them, as indicated in Fig. 4, in which the horizontal rollers are not provided on the guides.

From the foregoing description it will be observed that I have invented an improved bottom guide for the doors of freight cars which reduces the friction incident to the movement of the door relatively to the guides and hence renders the exertion of less power necessary in the opening and closing of the doors.

It is further evident that by the use of my improved guide the opening and closing of doors which have sagged in usage is facilitated as the bottoms of such doors rest upon and are supported by anti-friction rollers.

While I have described in more or less detail the specific embodiment of my invention herein illustrated, yet it will be understood that I do not wish to be limited thereto, but contemplate changes in form, the proportion of parts, and the substitution of equivalents as occasion may require, or as may be deemed expedient.

What I claim is:

1. A bottom door guide for freight cars comprising supporting means adapted to be secured to the car below the plane of the door opening, a horizontal plate projecting outwardly from said means, a vertically disposed roller mounted upon said horizontal plate and spaced outwardly from said supporting means in position to be engaged by the outer surface of the bottom of the door, and guide flanges mounted upon said horizontal plate on opposite sides of and aligning with the axis of said roller to protect the roller from injurious contact of the door, said flanges converging inwardly and terminating in a vertical plane outside of the inner surface of said roller to permit the engagement therewith of the outer surface of the bottom of the door.

2. A bottom door guide for freight cars comprising supporting means adapted to be secured to the car below the plane of the door opening, a vertically disposed roller spaced outwardly from said supporting means and adapted to be engaged by the outer surface of the bottom of the door, and a horizontally disposed roller adapted to underlie the lower edge of the door.

3. A bottom door guide for freight cars comprising supporting means adapted to be secured to the car below the plane of the door opening, a vertically disposed roller

- spaced outwardly from said supporting means and adapted to be engaged by the outer surface of the bottom of the door, inwardly converging guide flanges on the opposite sides of said roller, and a horizontally disposed roller adapted to underlie the lower edge of the door.
4. The combination with a freight car having a sliding side door, of a depending flange along the bottom of the door projecting below the door opening and a guide fixed to the car comprising a vertical roller engaged by the outer surface of said flange, and a horizontally disposed roller underlying the lower edge of said flange.
5. The combination with a freight car having a sliding side door, of a depending flange along the bottom of the door and a guide fixed to the car below the plane of the door opening comprising a vertical roller engaged by the outer surface of said flange, inwardly converging guide flanges at side of said roller, and a horizontally disposed roller underlying the lower edge of said flange.
6. The combination with a freight car having a sliding side door, of a depending flange along the bottom of the door projecting below the door opening, and a guide fixed to the car comprising a vertical roller engaged by the outer surface of said flange, said flange having an outward projection thereon in position to engage said roller when the door is closed and thereby force the door tightly against the frame around the door opening.
7. The combination with a freight car having a sliding side door, of a depending flange along the bottom of the door, a plurality of guides fixed to the car side below the plane of the door opening, one located adjacent the front and another adjacent the rear of the door opening, each of said guides comprising a vertical roller engaged by the outer surface of said flange, the rollers on the guides adjacent the front and rear of the door opening being located nearer the car side than the rollers on the other guides, and outward projections on said flange in position to engage the rollers on the guides adjacent the front and rear of the door opening when the door is closed.
8. The combination with a freight car having a sliding side door, of a depending flange along the bottom of the door, a plurality of guides fixed to the car side below the plane of the door opening, one located adjacent the front and another adjacent the rear of the door opening each of said guides comprising a vertical roller engaged by the outer surface of said flange, the rollers on the guides adjacent the front and rear of the door opening being located nearer the car side than the rollers on the other guides, outward projections on said flange in position to engage the rollers on the guides adjacent the front and rear of the door opening when the door is closed, and a horizontally disposed roller on each of said guides underlying the lower edge of said flange.
- In testimony whereof, I have subscribed my name.
